UNITED STATES PATENT OFFICE.

HORACE E. SMYTHE, OF PITTSBURGH, PENNSYLVANIA, ASSIGNOR TO THE S. R. SMYTHE COMPANY, OF PITTSBURGH, PENNSYLVANIA, A CORPORATION OF WEST VIRGINIA.

PREHEATING APPARATUS FOR FURNACES.

1,305,176.

Specification of Letters Patent. Patented May 27, 1919.

Application filed January 23, 1919. Serial No. 272,645.

To all whom it may concern:

Be it known that I, HORACE E. SMYTHE, a citizen of the United States, residing at Pittsburgh, in the county of Allegheny and 5 State of Pennsylvania, have invented new and useful Improvements in Preheating Apparatus for Furnaces, of which the following is a specification.

My invention relates to apparatus for pre- 10 heating air, gas, or both for furnaces.

The principal object of this invention is to provide a preheating apparatus for gaseous substance, as air and producer gas, for example, which has a minimum of horizontal 15 surfaces for the reception of dust, a maximum heating and radiating surface, and improved facilities for cleaning dust from the flue surfaces and from the apparatus itself.

Referring to the accompanying drawings, 20 Figure 1 is in part a plan and in part a horizontal section constructed in accordance with my invention; Fig. 2, a vertical section on the line II—II, Fig. 1; and Fig. 3, a vertical cross-section on the line III—III, 25 Fig. 1.

On the drawing, 1 and 2 designate a pair of structures for preheating air or gas preliminarily to their introduction into a furnace of the reversing type. 3 and 4 are the 30 necks leading to a reversing furnace, not shown, while 5 and 6 are passages leading to the stack 7 or to a supply of gas or air, according to the position of the reversing valves. As my invention lies entirely in the 35 structures 1 and 2, it is not necessary to illustrate the usual reversing valves and the usual passages by which these structures may be connected alternately to the stack and the air or gas supply.

40 As the structures 1 and 2 are alike, the structure 1 only will be described, in which 8 is the bottom or floor, 9 the top or roof, and 10 and 11 the sides. The structure 1 has a large chamber provided with several 45 baffles or walls 12, 13, 14, 15, 16, and 17. These baffles except 17 start alternately from the sides 10 and 11 and stop somewhat short of the opposite side, having a short-circuiting passage 13, so that from the neck 3 to the 50 passage 5 there is formed a tortuous or zig-zag regenerator flue or passage. The baffle 17 is shown as separated from the wall 11, so that the air or gas is divided on opposite sides thereof, but this baffle may reach the 55 wall 11 if the draft through the structure 1

is sufficiently strong. If necessary to increase the rate of flow of air or gas, the baffles 12 to 16, or some of them, may have the short-circuiting passages 18 in their walls in line with the passages 19 through 60 which the air or gas passes from one side of each wall to the other side thereof. The blind or closed end of the baffle 12 is placed opposite the neck 3 to prevent short-circuiting the passage between that baffle and the 65 adjacent end of the structure 1.

The upper ends of the baffles are braced by the arches 20, which bridge the spaces between consecutive baffles.

The sides of the structure 1 are provided 70 with arched doors 21 built opposite the several members of the said tortuous flue or passage so that they may be opened for the purpose of cleaning the interior and removing the accumulated dust, or other foreign 75 matter carried in suspension. These doors may be of any type, such as swinging or sliding, but I have shown them to be composed of removable walls filling the arched doorways. To clean the walls of this 80 tortuous passage, I insert air or steam nozzles through the openings 22 in the roof 9 adjacent to the faces of the several walls 12 to 17, and the rear wall 23. I do not confine myself to any specific location of the 85 openings 22 as they may be located adjacent to any portion of the said walls.

It will be understood, for example, that the hot waste gases from the furnace may enter the structure 1 by way of the neck 3, 90 whereby the exterior walls, the floor, the roof, and both sides of the baffles 12 to 17 will become highly heated, these gases finally leaving through the passage 5 on their way to the stack 7; and that at the 95 same time air or gas may pass through the passage 6 and the structure 2 and the neck 4, all preheated, to the said furnace. If one 100 pair of structures be used to preheat air, another pair may be provided to preheat gas, the air and gas being brought in a manner well known, to the furnace chamber. After the structure 1 has become highly heated by the waste gases and the structure 2 become cooled by the passage of 105 air or gas to the furnace, the flow of all the gaseous materials is reversed by the usual reversing valves, whereupon air or gas passes through the structure 1 on its way 110 to the furnace while the waste products of

combustion from the furnace pass through the structure 2 to the stack. When the structure 2 becomes highly heated again, the flow of all the gaseous materials is again 5 reversed. This alternation is continued while the furnace is in operation.

It is seen that my regenerator provides no horizontal surfaces for the collection of dust, and the clogging and the insulating 10 of the passages. I provide a maximum area of heating and radiating surfaces for the size of the structures 1 and 2, which may have any practical capacity and any practical number of baffles, with or without the 15 short-circuiting passages 13. No tearing down of the structures, except at the doorways, where brick doors are used, is required for cleaning them.

I claim:

- 20 1. In a preheating structure for air, gas, or the like, a chamber having an inlet and an outlet, and between the same a series of baffles arising alternately from the sides of the chamber and stopping short of the opposite side thereof, and also extending from the floor to the roof whereby a tortuous heating and radiating passage is provided between the said inlet and outlet, and short-circuiting passages in some of the baffles.
- 25 Signed at Pittsburgh, this 15th day of January, A. D. 1919.

HORACE E. SMYTHE.

Copies of this patent may be obtained for five cents each, by addressing the "Commissioner of Patents, Washington, D. C."

zontal places for the lodgment of dust are provided.

2. In a preheating structure for air, gas, or the like, a chamber having an inlet and an outlet, and between the same a series of baffles arising alternately from the sides of the chamber and stopping short of the opposite side thereof, and also extending from the floor to the roof whereby a tortuous heating and radiating passage is provided between the said inlet and outlet, and doors in the sides of the chamber opposite the members of the said passage and no horizontal places for the lodgment of dust are provided.

3. In a preheating structure for air, gas, or the like, a chamber having an inlet and an outlet, and between the same a series of baffles arising alternately from the sides of the chamber and stopping short of the opposite side thereof, whereby a tortuous heating and radiating passage is provided between the said inlet and outlet, and short-circuiting passages in some of the baffles.
